MEMORIAL ELECTRIC LIGHT

Arieh Feld, Hirsch St. 7, and Yeruham Feld, Tiberius
St. 28, both of Bnei Brak, Israel

Filed Sept. 12, 1973, Ser. No. 396,631

Claims priority, application Israel Mar. 19, 1973

Term of patent 14 years

Int. Cl. D26—05; D11—02

U.S. Cl. D48—20 E

Fig. 1

FIG. 1 is a front view of a memorial electric light showing our design; and

FIG. 2 is a perspective view of the memorial electric light of FIG. 1.

The rear of the light is flat and unornamented.

We claim:

The ornamental design for a memorial electric light, as shown and described.
